PIPE HANGER SYSTEM

William F. Bach, Cleveland Heights, Ohio

Application September 30, 1943, Serial No. 504,354

10 Claims. (Cl. 248—59)

The present invention relates to a pipe hanger system comprising a small number of simple elements of universal adaptability and associability in a variety of ways, by means of which a large number of different constructions for the suspension of a single pipe line or a system or systems of pipe lines of the same or different sizes may be readily assembled, rearranged and dismantled as the case may require.

The pipe hanger mechanism according to my invention may be used for attaching conduits, water, gas, or other pipe lines, or a plurality of such lines, in various horizontal positions to an overhead support or mill building beams or in upright position to a vertical wall; it is adapted for use with any one of the conventional building materials, such as steel structural work, brick, concrete, wood, or plastics.

The main object of my invention is to provide a pipe hanger assembly comprising a few inexpensive parts, the combination of which will allow the adaptation of the device to any mode of attachment of pipes as may be required in the building art.

One object of the invention is to make the elements easy to secure in position and to be adjustable without detaching the same.

Another object is the manufacture of the hanger elements from a single piece of unbreakable material.

A further object of the invention is to produce a hanger arrangement that will permit spacing of the pipes or pipes supported thereby at any desired distance from the overhead supporting structure, or vertically as desired.

Yet another object of the invention is to provide a rail of particular profile associated with other of the hanger elements in which certain of the hanger elements may be readily shifted to and held in any desired position at the time the piping is being installed.

Another object of my invention is to provide an arrangement for suspending a plurality of hangers at different levels and angles with respect to the supporting structure.

Further objects of the present invention will appear from the following description with reference to the accompanying drawings.

The above mentioned elements from which the pipe support may be assembled comprise a hanger proper having two arms with flanged ends for receiving a locking bolt and a top portion of novel design which makes it capable of engagement with a hanger housing in any desired position and of easy sliding movement thereon. The hanger housing, which is the second of the above mentioned elements, is channel-shaped; it is provided with longitudinally extending flanges for the engagement with the above mentioned slots of the hanger top and has several slots on the main web for receiving connecting bolts by means

of which the casing is fastened to the supporting structure of the pipe hanger. A third element to be used in the combination is a C-shaped clamp such as is commonly used with I-beams; the clamp is threaded at both clamping ends and fitted with a set screw that clamps it to the flange of the beam or angle iron.

The above mentioned elements will be more fully described hereinafter with reference to the accompanying drawings and the various applications thereof will be illustrated in a number of examples. It should, however, be understood that the means and combinations thereof disclosed in the specification and drawings are but a few of the embodiments in which the principles of the invention may be applied and that it is not intended to limit the claims to the exact construction shown and described.

In said annexed drawings:

20 Fig. 1 is an illustration of the pipe hanger with top portion of novel design;

Fig. 2 shows the hanger in side elevation with a portion of a pipe supported therein;

Fig. 3 is a perspective view of the channel-shaped housing;

Fig. 4 shows the hanger in engagement with the housing;

Fig. 5 shows in section a housing, a hanger suspended thereon and a portion of a pipe fitted therein;

Fig. 6 is a section taken along line B—B of Fig. 5;

Fig. 7 illustrates the hanger as affixed to an overhead structure by bolt connection and a supported pipe in section;

Fig. 8 is a side view of the above;

Fig. 9 is a perspective view of two vertical pipes attached to a channel-housing;

Fig. 10 is a view, partly in elevation, partly in section of a hanger with pipe supported therein, attached to an angle iron by means of a C-clamp;

Fig. 11 shows the clamp alone in elevation;

Fig. 12 is a section of the clamp along line A—A of Fig. 11;

Fig. 13 is a view partly in elevation, partly in section, of a hanger with pipe attached to an I-beam by means of a C-clamp;

Fig. 14 shows a clamp and a hanger-rod screwed thereto and fastened to an angle-iron;

Figs. 15 and 16 show a retaining clip as used in several applications, in plan and elevation respectively.

Fig. 17 is a perspective view, with parts of the housing broken away, showing said housing and three hangers attached thereto;

Fig. 18 is another application of one housing and three pipe hangers at different levels and angles with respect to the housing;

60 Fig. 19 shows a housing carrying three pipe

hangers and being clamped to an I-beam by means of two C-clamps;

Fig. 20 is another application of a housing with three hangers, in which the hangers are suspended on rods at different angles, the housing being clamped to an angle-iron; and

Figs. 21 to 24 show some more combinations for the arrangement of a plurality of pipes of different sizes, disposed, at different levels and angles with respect to the supporting structure.

The elements for building up the various structural embodiments of the present invention are shown in Figs. 1 to 6, 11 and 12. The pipe hanger proper, generally indicated by 5, comprises a top portion 6 which has a web 7 with a central opening 8 and rectangularly bent side portions 8. The latter have four slots 10 formed therein which serve for engagement with the housing 12. The hanger has two curved arms 13 for gripping a pipe P. The lower ends of said arms 13 terminate in flanges 14 which receive a threaded bolt 15 that serves for drawing the end portions together when a pipe is in position, in which it may be locked by nut 17. The dimensions of the curved arms 13 and the shape thereof relative to the circumference of the pipe to be suspended are such that the pipe is forced into contact with the housing 12 when the bolt and nut 15-17 are tightened.

The housing 12 has a web portion 18, depending side portions 19 and inwardly bent flanges 20, which serve for engagement with slots 10 of the hanger. The dimensions of the slots 10 relative to the dimensions of the flanges 20, are such that the hanger proper can be slid readily along the flanges 20 and to permit the pipe clamping action above referred to. The web 18 has, in the example shown in the drawings, three anchor slots; when one beam clamp or ceiling anchor is used it is fastened through the center slot 21, when two clamps or coiling anchors are used they are fastened through slots 22. At the ends the housing is equipped with cotter pins 23, which are used for locking a plurality of pipes in the housing and will prevent their sliding out of the housing at a time when they are moved, for instance, for rearrangement.

The four slots 10 are made loosely to fit the flanges 20 so that the hanger may easily be moved to any desired point in the housing. Locking and unlocking of a pipe in the hanger is easily accomplished by tightening or loosening bolt 15. As best shown in Fig. 6, upon tightening of bolt 15 pipe P is pressed against the flanges 20 and is immobilized thereby, independently of whether the housing be disposed in horizontal or vertical position.

Figs. 7 to 9 show some applications for the fastening of pipe lines in horizontal or vertical planes by aid of the elements so far described.

Figs. 7 and 8 show the attachment of a single pipe to a concrete ceiling C. In this case the housing 12 may be omitted and a single bolt 5 may be used for fastening the hanger by being passed through hole 9. This attachment is not only very simple, it also makes it possible to run the pipe in any desired direction. In a similar way a pipe could be fastened in a vertical plane by anchoring it in a vertical support.

Fig. 9 shows the attachment of two pipes in a vertical plane by means of a housing. The number of pipes could be varied as desired. The advantage of this construction is easy rearrangement within the vertical plane in case another spacing of the pipes should become desirable.

It will be readily understood that a similar construction could be used for laying a plurality of pipes parallel to each other in a horizontal plane.

In the attachments shown in Figs. 7 to 9 the pipe lines are suspended or supported in close proximity of the building structure. This is convenient for purposes of electrical installations. In other cases, such as the installation of steam pipes, it is common usage to dispose the pipes at a certain distance of the supporting structure to allow for expansion by heat or for the purpose of radiation. Examples of such attachments will be given below and are illustrated in Figs. 14, 18 and 20.

In Figs. 11 and 12 I illustrate the C-clamp which forms another element for the construction of pipe lines according to the principles of my invention.

The C-clamp shown in Figs. 11 and 12 has the two clamping arms 25 with enlarged ends 24 bored at 26, each bore being internally threaded. One of these threaded bores receives a bolt 27 which serves for clamping a hanger to an I-beam or similar element of construction. The other threaded bore serves for receiving an element which is to be brought into clamping engagement with said structural element. Thus it is shown in Fig. 13 that the lower bore 26 receives a bolt 28 for connecting a hanger to said clamp and in Fig. 14 it is illustrated as receiving a hanger rod 29.

In some cases where there is intense vibration it is desirable to use a retaining clip 30 as shown in Figs. 15 and 16 for securely fastening to a beam I or angle iron a. One end of clip 30 is cut out at 33 to form two prongs 34, which are slipped past the thickened end 24 of the clamp and bent down as shown in Figs. 13 and 14. The other end of the clip may be bent to engage with the structural element as shown at 32 in Figs. 13 and 13a in Fig. 14.

A similar application to the ones just described is shown in Fig. 10, where a pipe hanger 5 is fastened to an angle iron a by means of a clamp without interposed retaining clip, the position of the hanger and angle being inverted as compared to Fig. 14.

As mentioned before the pipe hanger according to my invention is very well adapted for attaching multiple lines of pipe to horizontal or vertical supporting structures. Figs. 17 to 20 inclusive, illustrate examples in which three pipe lines may be fastened by different ways of attachment to concrete ceiling or to horizontal beams.

In Fig. 17 the housing 12 may be attached to an overhead support by bolt b. The housing carries three hangers in engagement with flanges 20. For inserting pipes, bolts 15 are unscrewed and as soon as the pipes are in proper position the bolts are tightened for locking.

Due to the strength of the housing, which is made of heavy gauge steel, it is possible to make many installations while using a single anchor bolt as shown in Fig. 17. In this case the housing can be adjusted on the ceiling so that the pipes can be run in any desired direction.

If it is desired to hang the pipes at different levels an arrangement as shown in Fig. 18 may be applied. In this case nuts 36 are provided of a size that will allow them to remain in sliding engagement with flanges 20 of the housing 12. The nuts are connected with the hangers by means of rods 38 and 39 which may be of

various desired lengths. When the hangers are thus suspended by nuts and rods the pipes may be run in any direction, regardless of the fact whether one anchor bolt or two anchor bolts are used for attaching the housing to the building structure. The rod-and-nut suspension of the hangers may be combined with the direct channel engagement of some of the hangers, as likewise shown in Fig. 18 of the right-hand side of the figure.

Figs. 19 and 20 show how multiple lines of pipe may be attached to an I-beam. This is a further development of the arrangement shown in Figs. 10, 13 and 14. When it is desired to attach a plurality of parallel pipes to the underside of an I-beam running parallel thereto the housing 12 may be fastened to the beam by means of two C-clamps as shown in Fig. 19. In case it is desired to run the set of pipes at right angles with the beam the housing has to be clamped to one flange of the beam as shown in Fig. 20. This figure further shows the modified arrangement in which pipes are suspended on nuts 36 by means of rods 38 of various lengths, which arrangement allows the running of pipes in different directions and at any desired level.

Fig. 21 shows another embodiment of the invention in which one set of hangers is arranged on top of a housing 12 and another set of hangers at the bottom thereof. In this case the attachment of the top row of hangers is accomplished by tapping the web 18 of the housing and screwing the hangers 5 thereto as at 40. Hangers of different sizes may be used if desired. At the bottom of housing 12 the flanges 20 may be used for suspending thereon hangers 5, by means of the interengaging slots 10, as shown at 41, or by rod-and-nut connection, as shown at 42. Two rods 43 are, moreover, provided for suspending the housing at any desired level.

A similar arrangement of different sets of pipe hangers is illustrated in Fig. 22, the difference being that two housings are used in end to end position for the attachment of all the pipe hangers.

The unusual flexibility of arrangement for a plurality of pipe lines of which the construction is capable is exemplified by Figs. 23 and 24.

Fig. 23 shows an arrangement of three housings, one of which, 12a, is disposed horizontally, while the other two, 12b, are disposed at right angles thereto. This arrangement of housings is effected by means of angles 45 to which the housings are secured by bolts at 46. The vertically disposed housings 12b each carry a plurality of hangers 5 for the support of sets of parallel pipe lines. The horizontal housing 12a is shown to support a set of pipe hangers at the under side and a single hanger of larger size on top. Evidently this arrangement is capable of a number of further variations which will be understood by any person skilled in the art without further explanation.

Fig. 24 finally shows an arrangement in which two housings 12 are combined at right angles to each other, the upper housing supporting on its inverted channel a hanger disposed between two angles a, which angles are themselves affixed to the upper housing by means of two C-clamps. The lower housing is riveted to the upper one and carries on its under side a desired number of hangers which will support pipes running in a direction at right angles to the direction of the upper pipe P.

In this case, too, many other variations will readily present themselves to anyone skilled in the art, particularly in combination with the examples described and shown in several of the other figures.

To contractors, plumbers, steam fitters, industrial electricians and millwrights it will be apparent that I have disclosed a pipe hanging system comprising a few elements of simple, sturdy construction and the use of which will eliminate a great deal of labor in drilling, sawing and fitting of hanger straps and similar manual iron working while on the installation job. The parts are interchangeable and adaptable to ready securing to a variety of mill building constructions and inspection and repair or replacement of any one of a number of pipe lines arranged in clusters can be accomplished in an expeditious manner.

To those skilled in the art it will be apparent that other combinations and assemblies of the interfitting and interchanging of parts in accordance with the dictates of the requirements of the particular installation can be effected readily. In some instances cluster assemblies, such as indicated in Figs. 18, 20, 22, 23 and 24 can be brought together in a loose fashion with the various slideable elements retained in place by the cotter pins and at the shop before shipment to the place of installation. It will also be apparent to those skilled in the art that the degree of the clamping action of the hanger member proper upon a steam line or line subject to longitudinal expansion and contraction under varying thermal conditions will lie within the judgment of the mechanic making the installation.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. In a device for supporting pipes in combination a pipe hanger, a channel-shaped housing for receiving said pipe hanger and fastening it to a building structure, said housing having a web and longitudinal flanges parallel to said web, said pipe hanger having two curved pipe engaging arms, flanged ends on said arms, a bolt for tightening said flanges over a pipe in position and a channel-shaped head integrally formed with said arms, said head having slideways for receiving the flanges of said housing for a guided sliding movement.

2. In a device for supporting pipes in combination a pipe hanger, a housing for receiving said pipe hanger and fastening it to a building structure, said housing having a web with a plurality of slots for attachment to said building structure and longitudinal flanges parallel to said web, said pipe hanger having two curved pipe engaging arms, flanged ends on said arms, a bolt for tightening said flanges over a pipe in position, and a head integrally formed with said arms, said head having slideways for receiving the flanges of said housing for a guided sliding movement.

3. In a device for supporting pipes in combination a pipe hanger, a housing attachable to a building structure for receiving said pipe hanger, said housing having a web with a plurality of slots for attachment to a building structure and longitudinal flanges parallel to said web, said pipe

hanger having two curved pipe engaging arms, flanged ends on said arms, a bolt for tightening said flanges over a pipe in position, and a head integrally formed with said arms, said head having a bore for receiving one end of a hanger rod, means for holding said hanger rod in engagement with said head, a nut in slideable engagement with said flanges on said housing, said nut having a threaded bore for engagement with the other end of said hanger rod whereby the hanger may be disposed at any desired angle with respect to the housing and at any desired distance from the housing.

4. In a device for supporting pipes in combination a plurality of channel shaped housings in back-to-back position, said housings being adapted to receive a plurality of pipe hangers in sliding engagement, each of said pipe hangers having two pipe engaging arms, means for tightening said arms over a pipe in position and means for mounting said hangers in sliding engagement with said housing.

5. In a device for supporting pipes in combination a pipe hanger, a channel-shaped housing for receiving said pipe hanger and supporting it in a building structure, said pipe hanger having two pipe engaging arms, means for tightening said arms over a pipe in position, a head integrally formed with said arms having slideways for sliding engagement with the flanges of said channel housing, a like channel housing pivotally connected in back-to-back relation to the first named housing and means affording adjustable attachment of the second channel housing to a building structure.

6. In a device for supporting pipes in combination a plurality of pipe hangers, a channel-shaped housing for receiving said pipe hangers and supporting them on a building structure, said pipe hangers having two pipe engaging arms, means for tightening said arms over a pipe in position, and a head integrally formed with said arms, said head having slideways for sliding engagement with the flanges of said channel housing, a like channel housing connected in back-to-back relation to the first named housing, means for fastening the two channel housings together so as to include any desired angle between them, a plurality of hangers in said second channel housing and means for attaching said second channel housing to a building structure.

7. In a device for supporting pipes in combination, pipe hanger means, a pair of channel-shaped stamped members having inturned flanges spaced

apart to provide slots, said channel members being arranged in back-to-back relation with the slots exposed, pivotal means securing said members in said back-to-back relation whereby one channel member may be swung to an angle relative to the other member while being supported by said member, means disposed within the slots of one channel member and adapted to be attached to a building structure, said pipe hanger means having a slideway head integrally formed thereon for engagement with the slots of said other channel member.

8. In a device for supporting pipes in combination a pipe hanger, a channel shaped housing for receiving said pipe hanger whereby the hanger can be suspended on a building structure, said pipe hanger having two curved pipe engaging arms, flanged ends on said arms, means for tightening said flanges over a pipe in position and the hanger having a head integrally formed with said arms, said hanger head being shaped to have shoulders in sliding engagement with longitudinally extending flanges on the housing, said pipe engaging arms being so dimensioned with respect to said pipe that they will force the pipe into contact with said housing when the arms are tightened upon the pipe and said hanger head shoulders will be tightened upon the housing flanges.

9. In a device for supporting pipes, a pipe hanger formed of flat band metal, two curved pipe engaging arms and an integral arm connecting head portion, and means for tightening said arms over a pipe in position and said head having slideways notched in the sides of the band metal above the curved pipe engaging arms for sliding and tightening engagement with an element capable of attaching the pipe hanger to a building structure.

10. In a device for supporting pipes in combination a channel-shaped housing, said housing having opposed flanges spaced to receive unitary pipe hangers, a plurality of pipe hangers in sliding engagement with the flanges, each of said pipe hangers having two curved pipe engaging arms, flanged ends on said arms, means for tightening said flanges over a pipe in position and a head integrally formed with said arms, said head having slideways for receiving the flanges of said housing for a guided sliding movement and serving to react upon the said flanges when said tightening means tightens the hanger arms about a pipe.

WILLIAM F. BACH.
